(57) CLAIM

The ornamental design for ornamentation for a table top and legs, as shown.

DESCRIPTION

FIG. 1 is a view of the ornamentation for a table top and legs in an embodiment of the present invention; and,

FIG. 2 is a view of the ornamentation of the legs of a table in an embodiment of the present invention. The ornamentation on the legs on the opposing side of the table shown in FIG. 2 is a mirror image of the ornamentation on the legs on the side shown in FIG. 2.

The broken lines in the figures are for purposes of showing environment and form no part of the invention.
